DESIGN FOR A SCISSORS HONE

Earl Todd, Kokomo, Ind., assignor to Aerl, Inc.,
a corporation of Indiana

Application July 31, 1945, Serial No. 121,111

Term of patent 7 years

(Cl. D37—1)

To all whom it may concern:

Be it known that I, Earl Todd, a citizen of the United States and a resident of Kokomo, county of Howard, and State of Indiana, have invented a new, original, and ornamental Design for a Scissors Hone, of which the following is a specification, reference being had to the accompanying drawing, forming part thereof.

In the drawing: The figure is a perspective view of a scissors hone showing my new design.

I claim:

The ornamental design for a scissors hone, as shown.

EARL TODD.
